(57) **CLAIM**

The ornamental design for an instrument for testing a thickness of a tendon graft, as shown and described.

DESCRIPTION

FIG. 1 is a top perspective view of an instrument for testing a thickness of a tendon graft in accordance with the new design; FIG. 2 is a left side elevation view thereof, the right side being a mirror image thereof;

FIG. 3 is a bottom elevation view thereof;

FIG. 4 is a top elevation view thereof; and,

FIG. 5 is a rear elevation view thereof.
